SINKING SHAFTS AND BOREHOLES

Filed March 18, 1925

FIG. 1.

FIG. 2.

FIG. 3.

Inventor:
Wilhelm G. Minuth

By Frishman
Atty.

UNITED STATES PATENT OFFICE.

WILHELM G. MINUTH, OF CELLE, GERMANY.

SINKING SHAFTS AND BOREHOLES.

Application filed March 18, 1925, Serial No. 16,342, and in Germany August 19, 1924.

My invention refers to the art of sinking shafts and bore holes down to the greatest depths, more especially through quicksand. It is a particular object of my invention to provide means whereby the sinking of shafts and bore holes can be effected in a cheaper and more convenient manner than was hitherto possible.

According to the practice hitherto adopted in the great majority of cases the drill or jet of water used for excavating the soil or rock is made to work in the hollow of a tubing extending below ground and which was allowed to be lowered in the bore hole by its own weight or under pressure applied from above in proportion as the excavation effected by the drill or the like proceeded. On a certain depth being reached, which in many cases did not exceed about 20 metres, the tubing would stick fast in the surrounding rock and would not sink down further. This necessitated the introduction into the tubing of another tubing the external diameter of which was less than the internal diameter of the first tubing and which now started descending along with the drill or the like. After a further 40 metres the second tubing would stick fast also and a third tubing of still inferior diameter had to be inserted and so on. Obviously owing to the high costs of the tubings this mode of proceeding is very expensive. Apart therefrom the gradual decrease in the diameter of the tubular space enclosing the drill prevented the use of larger drills and the obtention of bore holes of large diameter.

According to the present invention the sticking fast of the first tubing is effectively prevented by inserting between the outer wall of the tubing and the rock a liquid or viscous layer of annular diameter which not only separates the tubing from the rock, thereby preventing it from adhering, but owing to its pressure exerted on the inner wall of the pit or bore hole effectively prevents the caving in of rock or sand and the breaking in of water, gas, petroleum or the like which may be present in the rock. I prefer using a liquid or viscous mass having a higher specific gravity than water, and in many cases I have found it useful to employ a clay suspension or slime such as has already been used as a packing for loose rock and for layers containing water, gas and petroleum.

I will now proceed to describe my inven-

tion more particularly with reference to a device embodying same and which can be used with advantage for carrying my invention into effect.

In the drawings affixed to this specification and forming part thereof, such device is illustrated diagrammatically by way of example.

In the drawings,

Fig. 1 is a longitudinal section of the device in operative position in a bore hole,

Fig. 2 is a similar view of part of the lower portion of the device and

Fig. 3 is a cross section on the line 3—3 in Fig. 2, drawn to a larger scale.

Referring to the drawings, 5 is the tubing inserted in the bore hole and 6 is a sealing tube sharpened at its lower edge and mounted on the lower end of the tubing. This tube should have a length of about 5 meters, but shorter and longer tubes can be used with advantage in certain cases. The inner diameter of the tube 6 is about equal to the inner diameter of the tubing 5, but the outer diameter is considerably greater, exceeding the outer diameter of the tubing for instance by 50 to 70 mms. Obviously, when the tube 6 is lowered into the rock following the excavation produced by the drill 8 or other boring means, its outer diameter will predetermine the inner diameter of the bore hole. The outer diameter of the tubing 5 being considerably smaller, an annular space will be formed between the tubing 5 and the inner wall of the bore hole, and the tubing will therefore be prevented altogether from coming in contact with the bore hole wall. In order, however, to prevent the rock from caving in or water, gases or oil from breaking into this annular space, I keep the space filled with a stationary liquid or viscous body, having preferably a higher specific gravity than water.

Obviously the great length of the sealing tube 6 enables it to work after the manner of a piston, and to prevent the liquid or viscous packing from finding its way below the shoe.

Before starting the boring operation I prefer sinking a pit 1 having a depth of a few metres. This pit is lined in some suitable manner and through an opening in the center of the bottom lining 2 there is sunk into the rock a short tube 3, the inner diameter of which is equal to the diameter of the bore hole. The upper screw-threaded end 4 of

the tube preferably projects somewhat above the bottom lining 2 of the pit. Through the tube 3 the drill 8 and the sealing tube 6 are introduced and in proportion as the boring

operation proceeds, the tubing is lengthened.

The pit 1 and the annular space 7 between the tubing 5 and the wall of the bore hole are filled with a mass having a higher specific gravity than water, such as

10 for instance a slime formed of a watery suspension of clay. The shaft 1 serves as a reservoir for permanently keeping the space 7 filled with a stationary column of the slime. Inasmuch as owing to this ar-

15 rangement a sticking fast of the tubing in the bore hole cannot take place, all friction between the tubing and the bore hole being excluded, a single tubing of constant diameter can be used down to the greatest

20 depth.

In case that at greater depths the liquid filling the annular space 7 above the sealing tube 6 should become too viscous, I have provided means whereby it can at any mo-

25 ment be diluted with water through the shoe. To this end the tube 6 is mounted in the lower end of the tubing for angular motion within certain limits which are pre-determined by a stop or stops 11 projecting

30 into a corresponding notch or notches 12 in the lower end of the tubing. Channels

9 and 10 extending across the sealing tube 6 and the tubing respectively can be made to register by turning the tubing in the tube until the stop 11 meets the lateral wall of the notch 12. If water is now introduced into the tubing it will escape through the channels 10, 9 and will dilute from below the column of slime 7. In a similar man-

40 ner the entire column of slime can be replaced from below by pure water or by a slime of higher specific gravity. This latter step will prove necessary for instance where the bore hole meets a spring or natural gas.

45 In such cases the tube 3 can further be lengthened so as to project above ground or it can be packed by means of a stuffing box, and slime or the like can be forced into the annular space between the bore hole wall and the tubing by means of a forcing pump, until the necessary pressure acting on the bore hole walls is obtained.

55 The long sealing tube 6 further allows taking precautionary measures in case that eruptive rocks are met with, inasmuch as the long tube always precedes the column of liquid by several metres. The great length of the tube further warrants an exactly rectilinear boring. It can be extracted at any time for the purpose of sharpening it without any danger of rock caving in, provided only that the bore hole be filled with slime or other liquid.

65 The novel process here described is par-

ticularly adapted for use with percussion or rotation boring, wherein a current of water is sent down through the tubing, because in this way large samples of rock will continuously be raised to the surface. 70

After the boring operation has come to an end, I can either extract the tubing and sealing tube or I can replace the liquid column 7 by a filling of concrete or the like.

I wish it to be understood that I do not 75 desire to be limited to the particular character and sequence of operations or to the particular details of construction shown and described, for obvious modifications will occur to a person skilled in the art. 80

I claim:—

1. The method of sinking bore holes, pits, shafts and the like comprising boring into the rock, subdividing the bore hole thus obtained into a central space of cylindrical cross section and an outer space of annular cross section and forming in said outer space a stationary body of a non-solid mass. 85

2. The method of sinking bore holes, pits, shafts and the like comprising boring into the rock, subdividing the bore hole thus obtained into a central space of cylindrical cross section and an outer space of annular cross section and keeping said outer space filled with a stationary body of a substantially liquid mass. 90

3. The method of sinking bore holes, pits, shafts and the like comprising boring into the rock, subdividing the bore hole thus obtained into a central space of cylindrical cross section and an outer space of annular cross section and keeping said outer space filled with a stationary body of a non-solid mass of higher specific gravity than water. 100

4. The method of sinking bore holes, pits, shafts and the like comprising boring into the rock, subdividing the bore hole thus obtained into a central space of cylindrical cross section and an outer space of annular cross section and keeping said outer space filled with a stationary body of a watery suspension of clay. 105

5. The method of sinking bore holes, pits, shafts and the like comprising boring into the rock, subdividing the bore hole thus obtained into a central space of cylindrical cross section and an outer space of annular cross section, keeping said outer space filled with a stationary body of a non-solid mass and varying the physical properties of said mass. 115

6. The method of sinking bore holes, pits, shafts and the like comprising producing an excavation several metres in depth, lowering into the rock a short tube from the bottom of this excavation, boring into the rock through this tube, lowering into the bore hole thus produced a sealing tube and a tubing of considerably smaller diameter fitted to said tube and keeping said excavation and 120

130

the space between said tubing and the bore hole filled with a stationary body of a liquid.

7. Apparatus for sinking bore holes, pits, shafts and the like comprising excavating means, a tubing of even diameter surrounding said excavating means, a sealing tube at the end of said tubing, the outer diameter of said sealing tube being considerably greater than the diameter of said tubing and at least equal to the diameter of said excavating means and means for establishing from above ground communication between the interior of said sealing tube and the space surrounding said tubing.

8. Apparatus for sinking bore holes, pits, shafts and the like comprising excavating means, a tubing surrounding said excavating means and a sealing tube of considerably greater diameter at the end of said tubing, said sealing tube and tubing having channels capable of being brought to register and of controlling the passage of liquid from the interior to the exterior of said tube and a stop on one of the parts limiting their relative angular movement.

In testimony whereof I affix my signature.

WILHELM G. MINUTH.
